UNITED STATES PATENT OFFICE

133,675

DESIGN FOR A NEGLIGEE

Raymond Halpern, New York, N. Y.

Application August 10, 1942, Serial No. 107,860

Term of patent 3½ years

To all whom it may concern:

Be it known that I, Raymond Halpern, a citizen of the United States, residing in New York city, in the county of New York and State of New York, have invented a new, original, and ornamental Design for a Neglige, of which the following is a specification, reference being had to the accompanying drawing, forming part thereof.

Fig. 1 is a front view of a neglige showing my new design, and

Fig. 2 is a rear view of the neglige shown in Fig. 1 on a reduced scale.

I claim:

The ornamental design for a neglige, substantially as shown.

RAYMOND HALPERN.
